CALEB E. SUMMERS, OF KANSAS CITY, MISSOURI, ASSIGNOR TO SUMMERS MOTOR DEVICES COMPANY, OF KANSAS CITY, MISSOURI, A CORPORATION OF MISSOURI.

THERMOSTATIC AIR-REGULATOR.

1,184,045.

Specification of Letters Patent. Patented May 23, 1916.

Application filed July 10, 1914. Serial No. 850,146.

To all whom it may concern:

Be it known that I, CALEB E. SUMMERS, a citizen of the United States, residing at Kansas City, in the county of Jackson and State of Missouri, have invented certain new and useful Improvements in Thermostatic Air-Regulators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to thermostatic air regulators for carbureters, and more particularly to a device of this character, which may be located between the carbureter and the intake manifold of an internal combustion engine; the principal object of the device being to provide a regulator of this character, which may be quickly attached to any motor to furnish an auxiliary supply of air for the cylinders, and whereby the supply is governed by absolute pressure in the intake manifold and the temperature and barometric pressure of the atmosphere. In accomplishing this object, I have provided the improved details of structure herein-after described and illustrated in the accompanying drawings, wherein:

Figure I is a side view of a motor equipped with a regulator constructed in accordance with my invention. Fig. II is a perspective view of the regulator. Fig. III is a longitudinal, sectional view of the device on the line III—III, Fig. II. Fig. IV is a transverse sectional view on the line IV—IV, Fig. II. Fig. V is a similar view on the line V—V, Fig. II.

Referring more in detail to the parts: 1 designates a motor of ordinary construction having an exhaust manifold 2, an intake manifold 3, and a carbureter 4, all of which parts are well known in the art and need not be described in detail.

Located between the carbureter and the intake manifold, is a thermostatic air regulator 5 comprising a casting 6 having a flat head 7 provided with an air chamber 8, which communicates with the chamber 9 of a thermostatic device 10, both of said chambers being inclosed by a flat plate 12 which may be soldered or otherwise secured to the

casting. The flat head 7 is oval-shaped to conform to the standard carbureter connection, and is provided with a laterally opening slot 14 and a rearwardly opening slot 15 for receiving the screws 16 of the intake manifold. The head 7 is also provided with a central opening 17 which registers with the intake and carbureter conduits and is provided with a plurality of inwardly opening apertures 18 which communicate with the air chamber 8.

Slidably mounted in the laterally opening slots 19 in the chamber 9 is a thermostat 20 comprising a plurality of arched units 21 consisting of two strips of metal having different expansion coefficients, such as brass and steel, soldered together with the brass piece on the bottom, so that when the temperature increases, the brass will tend to expand the greater and coact with the steel strip to lower the plug 22, which is connected therewith. The sides of the plug 22 are curved to conform to the theoretical requirements of the motor and the upper end of said plug projects through an aperture 23 in a diaphragm 24 which is held to a seat 25 on the portion 10 by means of a wire 26 that is yieldingly held in a laterally opening groove 27 by its own tension.

In using the device, the screws 16 are loosened, so as to drop the carbureter a short distance below the intake manifold and permit the flat head 7 to be inserted therebetween. The slot 14 is then moved over the first screw 16 and the whole regulator revolved to move slot 15 over the second screw in which position the opening 17 is in functional position and the screws are tightened. When the motor is running on a closed throttle, there is a greater vacuum in the intake manifold than when it is running with the throttle open, consequently if air is taken at a point between the motor and the throttle, considerable suction would be noticed at that point. In utilizing this principle, I have provided the apertured diaphragm 24 which is drawn downwardly by suction from the intake manifold and around the plug 22, so that a limited supply of air is delivered through the aperture 23 and air chamber 8 and discharged through the apertures 18 at right angles to the flow of gas from the carbureter, thereby thoroughly breaking up and mixing with any particles of fuel in suspension.

sion and eliminating any tendency of the fuel to creep along the sides of the manifold.

The above mechanism operates proportionately for all speeds, but as the motor warms up and the temperature of the surrounding atmosphere becomes greater, the air will expand and cause the fuel mixture to become too rich. The same increase in temperature causes the thermostat to expand and lower the plug 22, thereby increasing the area of the aperture 23 and supplying a greater amount of air to the intake manifold to maintain a uniform fuel mixture.

Having thus described my invention, what I claim as new therein, and desire to secure by Letters-Patent, is:

Claims:

20 1. The combination with an air distributing member, of a housing having its interior in communication with said member, an apertured diaphragm closing the housing, a thermostatic arch within the housing, and 25 a tapered plug on said arch projected into said aperture.

2. The combination with an air distributing chamber, of a housing having an interior chamber communicating with the distributing chamber, a flexible diaphragm on said housing having a central aperture therein, a thermostatic member in said housing and a tapered plug on said member projected through the aperture in said diaphragm.

3. The combination with an air distributing chamber, of a housing having an interior chamber in communication with the distributing chamber, a flexible diaphragm 40 closing the housing and having a central aperture therein, a thermostatic arch within the housing chamber, and a tapered plug mounted on said arch and projected through the aperture in said diaphragm, for the purpose set forth.

4. The combination with a motor having an intake manifold and a carbureter, of a device for introducing air into said manifold comprising a flat head having an interior chamber and a central aperture adapted 50 for registration with the carbureter and in-

take manifold, having a plurality of apertures opening from said interior chamber into said central aperture, a cylindrical member integral with said flat head and 55 having a chamber communicating with the interior chamber in said head, a tapered plug supported in the cylindrical member, and a flexible diaphragm fixed in said cylindrical member, and having a central aperture surrounding and spaced from said plug; the said diaphragm being adapted for movement by absolute pressure in the intake manifold for changing the relative positions of said diaphragm aperture and said tapered 60 plug to vary the area of the space therebetween.

5. The combination with a motor having an intake manifold and a carbureter, of a device for introducing air into said manifold comprising a flat head having an interior chamber and a central aperture adapted for registration with the carbureter and intake manifold, having a plurality of apertures opening from said interior chamber 70 into said central aperture, a cylindrical member integral with said flat head and having a chamber communicating with the interior chamber in said head, a thermostat in said chamber comprising a plurality of 75 arched units consisting of metal strips having different expansion coefficients arranged so that variation in temperature will change the height of said arched units, a tapered plug on said thermostat, and a flexible diaphragm rigidly secured in said cylindrical member and having a central aperture surrounding and spaced from said tapered plug, whereby variations in the absolute 80 pressure in the intake manifold will change the relative position between said diaphragm aperture and said tapered plug, and change the area of the space therebetween, irrespective of the change of the position of said plug due to said thermostat.

In testimony whereof I affix my signature in presence of two witnesses.

CALEB E. SUMMERS.
